[57] CLAIM

The ornamental design for a jack for subterranean meter pipes, as shown and described.

DESCRIPTION

FIG. 1 is a top plan view of a jack for subterranean meter pipes showing my new design;

FIG. 2 is a side elevational view thereof;

FIG. 3 is a front elevational view thereof;

FIG. 4 is an opposite side elevational view thereof;

FIG. 5 is a rear elevational view thereof; and

FIG. 6 is a bottom plan view thereof.
